VEHICLE SANDING DEVICE

Clyde C. Farmer, Pittsburgh, Pa., assignor to
The Westinghouse Air Brake Company, Wil-
merding, Pa., a corporation of Pennsylvania

Application July 22, 1937, Serial No. 155,073

21 Claims. (Cl. 291—15)

This invention relates to vehicle sanding devices, and more particularly to sanding apparatus for railway vehicles and trains.

The practice of sanding the track rails to improve the adhesion between vehicle wheels and rails is one that has been long in use. In some instances, the control of the sanding is so arranged that an operator may select and terminate it at will. In other instances the sanding is entirely automatic, as for example, whenever an emergency brake application is effected sanding is automatically accomplished, without requiring additional effort on the part of the operator.

In heretofore most commonly employed brake equipments for trains, sanding is accomplished on the locomotive or power unit only. With such limited sanding of the track rails it is apparent that the adhesion between wheels on the trailing vehicles and the rails may not be improved at all. Under such conditions there may and does occur considerable wheel sliding. This is, of course, highly objectionable for well known reasons.

In the operation and control of trains which are designed to operate at extremely high speeds, as for example the new light-weight, high-speed, trains which operate in the neighborhood of one hundred miles per hour or more, it is highly desirable that sand be deposited on the rails under each car, simultaneously, so as to insure the highest possible coefficient of adhesion between wheels and rails, and thus facilitate the making of a prompt stop and at the same time minimize the danger of wheel sliding. It is further desirable that a high degree of flexibility be provided in controlling the sanding on the several cars, so that it may be used to the best advantage and always with the utmost regard for safety.

It is, therefore, a prime object of the present invention to provide an improved automatic sanding control means for a train.

It is a further object of the invention to provide an improved automatic sanding control means for a train which incorporates features providing for a high degree of flexibility in controlling sanding.

A yet further object of the invention is to provide an improved automatic sanding means which incorporates desirable suppression features, controllable at the will of an operator, so that the operator may initiate or suppress sanding more in accordance with the dictates of his judgment at the time of or before initiating the application of the brakes.

A still further object of the invention is to provide an improved automatic sanding control ap-

paratus in which the automatic sanding may be suppressed before initiating or during service applications of the brakes, according to the will of the operator, but in which automatic sanding occurs with every emergency application of the brakes and cannot be suppressed by the operator.

A yet further object of the invention is to provide an improved automatic sanding control means of the electropneumatic type.

Other objects and advantages of the invention, dealing particularly with the construction and arrangement of apparatus, will be more fully understood from the detailed description of several embodiments of the invention which follows, which description is taken in connection with the attached drawings, wherein,

Fig. 1 shows in schematic and diagrammatic form an adaptation of a simple form of the invention to a brake equipment intended for a high speed passenger train.

Fig. 2 is a modification of the scheme shown in Fig. 1, the figure illustrating the apparatus shown only on the first car of the train.

Fig. 3 illustrates another form of the invention as adapted to a brake apparatus also intended for a high speed passenger train.

Fig. 4 is a modification of the scheme shown in Fig. 3, and shows in fragmentary form part of the apparatus only for the first car of the train.

Embodiment of Fig. 1

The brake system illustrated in this figure is intended to be a simplified form of that commonly known to the trade as the "HSC" high speed train brake equipment, and particularly described and claimed in the pending application of Ellis E. Hewitt, Serial No. 741,063, filed August 23, 1934, which application is owned by the assignee of the present application. This equipment is also described in Instruction Pamphlet No. 5,064, Sup. 2, published by The Westinghouse Air Brake Company, Pittsburgh, Pa., the aforesaid assignee. As here illustrated, the brake equipment includes only those essential parts of the "HSC" equipment necessary to a clear and full understanding of the instant invention. In practice, however, it is to be specifically understood that I contemplate the association of the invention with complete brake equipments of the "HSC" type, although not entirely limited to this precise type.

Considering now briefly the parts of the brake equipment illustrated, at least one brake cylinder 10 is provided for each car in the train, and the supply of fluid under pressure to and its release

from each brake cylinder is by way of a straight air pipe 11, which is connected on each car in the train to an application and release magnet valve device 12; or supply of fluid under pressure to and its release from the brake cylinder on each car may be by operation of a triple valve device 13. A double check valve device 14, of conventional design, is disposed between the triple valve device and straight air pipe on each car, so as to permit supply to the connected brake cylinder from one only of the two sources at any given time.

Each car in the train is provided with a supply reservoir 15, which is charged from the usual 15 brake pipe 16 by way of a one-way check valve device 17. Each car is also provided with an auxiliary reservoir 18, which is also charged from the brake pipe 16 through the triple valve device in the usual manner.

On the head end or control car only in the train there is provided a master switch device 20, which controls, through train conductors 21 and 22, the several application and release magnet valve devices 12 throughout the train. A 25 brake valve device 23 is provided to control both electropneumatic (straight air) and automatic applications of the brakes. A main reservoir 24 on the head end car provides the main source of supply of fluid under pressure, and is maintained charged from the usual compressor, not shown. A conventional type feed valve device 25 functions in the accustomed manner to deliver fluid from the main reservoir at a desired constant pressure.

As applied to the brake equipment illustrated, the improved automatic sanding means on each trailer car includes a sanding device 26, a sanding reservoir 27, and a sanding magnet valve device 28. This group of parts is not located 40 on the head end or power car for the reason that it is more desirable to have the sanding of the rails under this car dissociated with the brake apparatus and solely under the manual control of the operator, so that sanding may be effected 45 under the power car only during acceleration when there is no need for sanding under the trailer cars.

The automatic sanding apparatus on the power or control car includes a manually operated 50 pressure valve device 30, two fluid pressure operated switch devices 31 and 32, and a volume reservoir 33.

Considering now the parts above enumerated more in detail, the brake cylinder 10 on each 55 car is intended to operate any desirable type of friction brake. The double check valve device 14 is, as before stated, of conventional design, and functions to permit supply of fluid under pressure to the brake cylinder from either 60 the straight air pipe 11 or the triple valve device 13, depending upon which supply has the greater pressure.

The triple valve device 13 may be assumed to be of conventional design, and since the construction and operation of conventional triple valves are well known, it is deemed unnecessary to describe this device further.

The application and release magnet valve device 12 is embodied in a casing provided with a 70 supply valve 35 and a release valve 36. The supply valve 35 is urged toward seated position by a spring 37, and is actuated to unseated position by an electromagnet 38 when energized. In a similar manner, the release valve 36 is urged toward a seated position by a spring 39, and is

also actuated to an unseated position by an electromagnet 40 when energized.

When the supply valve 35 is seated and the release valve 36 is unseated, the straight air pipe 11 is connected to the atmosphere past the unseated release valve 36 and by way of an exhaust port 41. When the release valve 36 is seated this communication is closed, and when at the same time supply valve 35 is unseated communication is established between the connected supply reservoir 15 and the straight air pipe.

The master switch device 20 is preferably embodied in a casing made of electrically insulating material, such for example as hard rubber, Micarta or Bakelite, and has suitably secured 15 therein a flexible diaphragm 43, which is subject on its upper side to pressure of fluid in chamber 44 and on its lower side to pressure of fluid in chamber 45. Connected to the upper side of the diaphragm 43 is a stem 46 which is 20 insulated from but carries one member of a set of release contacts 48. These contacts control the energization of the release train conductor 21, as will be more fully explained presently. Connected to the lower side of the diaphragm 43 is a stem 49 which is insulated from but carries one member of a set of application contacts 50. These contacts control the energization 25 of the application train conductor 22.

The upper chamber 44 is connected to a control pipe 51 while the lower chamber 45 is connected to the straight air pipe 11. When the pressures in the two chambers 44 and 45 are exactly equal, the diaphragm 43 assumes a position such that release contacts 48 are held closed 30 and application contacts 50 are held open. When the pressure in chamber 44 exceeds that in chamber 45 by a predetermined amount, the diaphragm 43 is flexed downwardly to open release contacts 48 and close application contacts 40 50. When the pressure in chamber 44 does not exceed that in chamber 45 by said predetermined amount, and the pressures in the two chambers are not exactly equal, the diaphragm 43 will assume a position such that both sets of contacts 45 are held open.

The brake valve device 23 is preferably of a design like or similar to that shown and described in the aforementioned Hewitt application, Serial No. 741,063. Briefly stated, this brake 50 valve device comprises a self-lapping portion and a rotary valve portion, both portions being operated by a single handle 52. This handle has a release position, a plurality of service application positions (a service application zone), a 55 pneumatic service application position, an emergency application position, and a lap position.

In the release position of the handle 52 the brake pipe 16 is connected to a pipe 53 leading to the feed valve device 25, so that fluid under pressure is supplied to the brake pipe at feed valve pressure. Also, in the release position of the handle 52 the control pipe 51 is in communication with an exhaust port within the 60 brake valve device.

When the handle 52 is moved to any position in the service application zone, fluid under pressure is supplied to the control pipe 51 to a degree dependent upon the extent of movement of the handle into the service application zone. At 65 the same time, the brake pipe 16 is maintained charged.

When the handle 52 is moved to the pneumatic service application position, communication between the feed valve pipe 53 and the brake pipe 70 75

16 is closed, and the brake pipe is opened to the atmosphere through a restricted port so as to reduce brake pipe pressure at a service rate. At the same time fluid under pressure may be supplied to the control pipe 51 corresponding to the degree supplied when the handle 52 is at the end of the service application zone.

5 When the handle is moved to the emergency application position, the brake pipe 16 is connected to the atmosphere through an unrestricted communication such that brake pipe pressure is reduced at an emergency rate. At the same time, fluid under pressure is supplied to the control pipe 51 to a maximum degree.

10 15 The lap position of the brake valve handle is intended to be used in making pneumatic service applications, and according to the usual practice.

Considering now the manually operated valve device 30, this device includes a valve 55 which 20 is urged toward seated position by a spring 56, and which has secured thereto a fluted stem 57 terminating in a button 58. Connected to the valve device 30 is a pipe 59, which branches from the feed valve pipe 53, and another pipe 25 60 which leads to the pneumatic switch device 31.

30 When the valve 55 is seated communication between the pipes 59 and 60 is closed, and pipe 60 is connected to the atmosphere past the fluted stem 57. When the valve 55 is unseated, as by manually depressing the button 58, the fluted stem 57 moves downwardly far enough to close communication between pipe 60 and the atmosphere, while communication is opened between 35 pipes 59 and 60. When the pressure manually applied to the button 58 is released, spring 56 will seat the valve 55 and fluid under pressure supplied to pipe 60 will be released to the atmosphere past the fluted stem 57.

40 45 Considering now the pneumatic switch device 31, this device is embodied in a casing having disposed therein an abutment 61, which is subject on its lowermost side to the pressure of fluid in chamber 62 and on its uppermost side to pressure of spring 63. Secured to the abutment 61 is a stem which carries insulated therefrom a movable member of a set of contacts 64. These contacts are closed when the abutment 61 is in its lowermost position and are opened when the 50 abutment is actuated upwardly.

55 The casing of the switch device 31 has also disposed therein a disc type check valve 65, which is biased to a seated position by a spring 66. The check valve 65 is provided with a restricted port or choke 67. Fluid under pressure supplied to the pipe 60 will at a relatively low value unseat the check valve 65 to permit free flow to the aforementioned chamber 62 and to the volume reservoir 33 connected to this chamber, as shown. 60 When fluid under pressure is subsequently released from pipe 60, flow from chamber 62 and volume reservoir 33 is by way of the restricted port or choke 67 only.

65 Considering now the pneumatic switch device 32, this device is embodied in a casing having disposed therein an abutment 69, subject on its lowermost side to pressure of fluid in chamber 70 and on its uppermost side to pressure of a spring 71. Secured to the abutment 69 is a 70 stem which is insulated from but carries one member of a set of contacts 72. When the abutment 69 is in its lowermost position these contacts are open, and when the abutment moves upwardly these contacts are closed. Fluid under pressure is supplied to the chamber 70, to shift

the abutment 69 upwardly, by way of pipe 73 which connects with the aforementioned control pipe 51.

Considering now the sanding apparatus comprising the parts 26, 27 and 28, the sander 26 5 is preferably one of the conventional types now commonly employed, which operates upon the supply of fluid under pressure thereto to deposit sand on the track rails. The magnet valve device 28 controls the charging of the sanding 10 reservoir 27 and the supply of fluid under pressure from this reservoir to the sander 26.

This magnet valve device is embodied in a casing having disposed therein a double beat valve 74, which is urged to an upper seated position by a spring 75, and to a lower seated position by an electromagnet 76 when energized. When the double beat valve 74 is in upper seated position, as illustrated, communication is established between the supply reservoir 15 and the sanding 20 reservoir, on that car, by way of pipe 77 and a one-way check valve device 78. The sanding reservoir 27 is thus charged with fluid under pressure. When the double beat valve 74 is shifted to its lower seated position, the sanding 25 reservoir 27 is connected to the sander 26 and so long as the double beat valve remains in lower seated position supplies fluid under pressure to the sander until the supply is exhausted, it being understood that fluid supplied to the sander 30 leaks therefrom as sand is deposited on the rail.

Further understanding of this embodiment of the invention will be readily appreciated from the description of operation thereof, which now follows.

35

Operation of the embodiment of Fig. 1

The parts of the system shown in Fig. 1 are shown in the position they assume when the brakes are released, that is, when the brake valve 40 handle 52 is in its release position. The brake pipe 16 will thus be charged with fluid to feed valve pressure, and the several supply reservoirs 15 and several auxiliary reservoirs 18 will be charged from the brake pipe as previously indicated. In addition, the several sanding electromagnets 28 will be deenergized so that the connected sanding reservoirs 27 will also be charged.

45 50 Now if it is desired to effect a service application of the brakes by electropneumatic operation, the brake valve handle 52 is moved into the service application zone an extent or degree according to the desired degree of application of the brakes. Fluid under pressure will be thus supplied to the control pipe 51 to a corresponding degree, and will flow to the master switch chamber 44 and to the switch device 32.

55 In the master switch device the diaphragm 43 will flex downwardly to open release contacts 48 and close application contacts 50. Now when release contacts 48 were closed they established a circuit from a battery 80 to the release train conductor 21, which circuit includes, beginning at battery 80, conductor 81 and the release contacts 48. Since the release electromagnet 40 of 60 each application and release magnet valve device 12 is connected to this conductor, it will be apparent that when release contacts were closed each of these electromagnets was energized. Therefore, when release contacts 48 open each 65 of the release electromagnets is deenergized and the spring 39 in each valve device 12 then seats release valve 36, closing communication between the straight air pipe 11 and the atmosphere.

70 75 When application contacts 50 of the master

switch device are closed, application train wire 22 is energized from battery 80, as will be apparent, and the application electromagnet 38 in each application and release valve device 12 will be 5 then energized. As a result, supply valve 35 in each valve device 12 will be unseated and fluid under pressure will be supplied from the supply reservoir 15 on each car to the straight air pipe 11. From the straight air pipe fluid under pressure will flow past the double check valve device 14 to the brake cylinder 10 on each car, and thereby apply the brakes. When straight air pipe pressure attains a value slightly below control pipe pressure, diaphragm 43 will assume a position 10 in which both release contacts 48 and application contacts 50 are maintained in open position. The application will be then lapped and the degree of the application will correspond to brake valve handle position.

20 Now when fluid at a low pressure is supplied to the control pipe 51 and from thence to the switch device 32, the abutment 69 of this device is actuated upwardly to close the contacts 72. If at the same time the contacts 64 of switch device 31 25 are closed, as illustrated, a sanding train conductor 82 is energized from the battery 80. The electromagnet 76 of each sanding magnet valve 28 is connected to this sanding conductor, so that in each magnet valve device the double beat valve will be actuated downwardly to supply fluid 30 under pressure from the sanding reservoir 27 to the sander 26. As before described, this causes sand to be deposited on the track rails, thus increasing the adhesion between the vehicle wheels 35 and rails.

It follows, therefore, that whenever fluid under pressure is supplied to the control pipe 51, and the contacts of the switch device 31 remain closed, the sanding electromagnet on each trailer car in the train will be energized to cause sanding of the rails.

If, however, the operator should decide that sanding is unnecessary for a particular brake application, he may forestall or prevent the automatic sanding by merely depressing the button 58 of the manually operated valve device 30. Depressing the button 58 unseats valve 55 and supplies fluid at feed valve pressure to the switch device 31 and volume reservoir 33, as previously indicated. When the operator feels that sufficient pressure has been established in these two devices, he releases pressure on the button 58 thereby permitting valve 55 to close.

Now as fluid under pressure flows to chamber 55 62 in switch device 31, and to volume reservoir 33, the flow is unrestricted due to the unseating of check valve 65. But when the valve 55 is seated, fluid under pressure is released from the chamber 62 and volume reservoir 33 at a rate 60 dependent upon the size of the choke or restricted port 67 in the check valve 65. It follows, therefore, that when fluid pressure is established in chamber 62 the contacts 64 will be opened and will remain open until the pressure 65 in chamber 62 and volume reservoir 33 is diminished to the point where the spring 63 will again shift the abutment 61 downwardly. This time interval can be varied both by varying the pressure in chamber 62 and by varying the size of choke 67. It can be selected as equal to the 70 usual time required to decelerate the train, or a shorter or a longer time. My preference is to select it as slightly longer than the average deceleration time.

75 Since the valve device 30 is connected directly

to the feed valve pipe 53, it follows that the suppression of the automatic sanding feature may be effected before or after initiating the brake application. If the suppression takes place appreciably before the brake application is initiated, 5 and the time during which the contacts 64 of the switch device 31 are opened is approximately equal to the average deceleration time, it will be apparent that sanding may take place before the vehicle has been brought to a stop. If this is 10 undesirable the suppression should be delayed until, or initiated at the same time as, the brake application is initiated.

To effect a release of the brakes following a service application, the brake valve handle 52 is 15 returned to release position to release fluid under pressure from the control pipe 51. The master switch device 20 will then effect the operation of the several application and release magnet valve devices 12 to effect a release of fluid under 20 pressure from the brake cylinders. At the same time, fluid under pressure is released from the switch device 32, so that if the sanding train conductor 82 has not been previously deenergized by the opening of contacts 64 of switch 25 device 31, it will now be deenergized with the release of the brakes.

When it is desired to effect a pneumatic service application of the brakes, which is intended to be used only in the event that the electropneumatic portion of the equipment is inoperative, 30 the brake valve handle 52 is turned to the pneumatic service application position. Fluid under pressure is thereupon released from the brake pipe 16 at a service rate, so that the triple valve 35 devices 13 throughout the train respond to supply fluid under pressure to the brake cylinders 10, past the double check valve devices 14, to a degree dependent upon the degree of reduction 40 in brake pipe pressure.

If the self-lapping portion of the brake valve device 23 is also operated, and if the control pipe 51 is intact, fluid under pressure will be supplied to the switch device 32, to initiate automatic sanding unless the button 58 of the valve device 45 30 has in the meanwhile been depressed to prevent this.

To release the brakes following a pneumatic service application, the brake valve handle 52 is returned to release position to recharge the brake 50 pipe. The triple valve devices then function to release fluid under pressure from the brake cylinders in the usual manner.

When it is desired to effect an emergency application of the brakes, the brake valve handle 55 52 is turned to the emergency position, so as to release fluid under pressure from the brake pipe at an emergency rate and at the same time to supply fluid under pressure to the control pipe 51 to the maximum degree. From what has been 60 said before, it will be apparent that the application and release magnet valve devices 12 will supply fluid under pressure to the straight air pipe 11, and fluid under pressure in this pipe will flow to one side of each of the double check valve 65 devices 14. Concurrently, the triple valve devices 13 will operate to supply fluid under pressure to the other side of each of the check valve devices 14. It is intended that the supply to the straight air pipe 11 shall be to a higher degree, and that 70 therefore the double check valves will shift to open communication between this pipe and the brake cylinders, while closing communication between the triple valves and the brake cylinders.

The operation of the automatic sanding por- 75

tion of the equipment is substantially the same as described for a regular service application, and unless the operator has depressed the button 58 of the valve device 30 automatic sanding will result throughout the train.

To release the brakes following an emergency application the brake valve handle 52 is returned to release position, thereby recharging the brake pipe 16 and releasing fluid under pressure from the control pipe 51. The parts of the triple valves 13 will then move to release position, while the application and release magnet valve devices 12 will function to release fluid under pressure from the straight air pipe 11 and brake cylinders 10. It will be obvious from the foregoing description that sanding of the rails under each of the trailer cars will result automatically whenever an application of the brakes is effected, unless the operator has beforehand operated the valve device 30 to suppress the sanding. After automatic sanding has been initiated it may be terminated by the subsequent operation of the valve device 30.

25 *Modification shown in Fig. 2*

The modification shown in this figure deals only with the equipment on the head end car. The parts in Fig. 1 which are duplicated in Fig. 2 are indicated by like numerals with the subscript 30 "a" added. As may be seen, therefore, the new parts comprise a service sanding switch device 85, a suppression switch device 86 and an emergency sanding switch device 87.

Considering the new devices now in detail, the service sanding switch device 85 is embodied in a casing having disposed therein a flexible diaphragm 88 subject on one side to pressure of fluid in chamber 89 and on the other side to pressure of a spring 90. Attached to the diaphragm is a stem 91 carrying, through insulating member 92, one member of a set of contacts 93. When the chamber 89 is at atmospheric pressure, spring 90 is effective in holding contacts 93 open. When fluid under pressure is supplied to the chamber 89, and the pressure rises above a predetermined low value, the diaphragm 88 flexes to the right and when moved far enough effects closing of contacts 93.

The suppression switch device 86 is embodied in a casing having suitably disposed therein a flexible diaphragm 95 subject on one side to pressure of fluid in chamber 96 and on the other side to pressure of a spring 97. Attached to the diaphragm is a stem 98 which terminates in an L-shaped element 99, which has the end of one arm pivotally connected to a link 100, and which at the end of its other arm carries insulated therefrom one member of a set of contacts 101. The aforementioned link 100 connects to an arm 102 which is pivotally mounted at 103 to a stationary part 104.

The arm 102 carries a latch 105 slidably disposed in a guide member 106, attached to the arm 102, and a spring 107 acts between the end of the latch 105 and a spring stop member 108.

When the pressure in chamber 96 is at atmospheric pressure the spring 97 holds the diaphragm 95 in a lower position against a stop 110. The connected parts are then positioned as illustrated in Fig. 2. When fluid under pressure above a predetermined low degree is supplied to chamber 96, diaphragm 95 is actuated upwardly to simultaneously rotate the arm 102 in a clockwise direction and open contacts 101. The arm

102 moves upwardly until the guide element 106 strikes a stationary stop 111.

When the arm 102 is in its uppermost position, against stop 111, the left end 112 of the arm 102 acts as a stop for the diaphragm stem 91 of the service sanding switch device 85. That is to say, the arm end 112 prevents movement of the stem 91 sufficiently to close the contacts 93.

If at the time fluid under pressure is supplied to chamber 96 of the suppression switch device 10 96, the stem 91 is in its extreme right hand position, where contacts 93 are closed, the arm 102 will move upwardly, the latch 105 then engaging the right hand end of the stem 91 and retracting far enough to slide past the end of the stem 91. 15 As the guide portion 106 strikes the stationary stop 111, the latch 105 then moves to the left and above the right hand end of the stem 91, thus locking the lever 102 in its uppermost position so long as the stem 91 remains to the right. The 20 purpose of this arrangement will be more fully understood presently.

The emergency sanding switch device 87 is embodied in a casing having disposed therein a diaphragm 115 which is subject on its lowermost 25 side to the pressure of fluid in chamber 116, constantly open to the brake pipe 16a, and on its other side to the pressure of spring 117. Attached to the diaphragm 115 is a stem 118 which carries insulated therefrom one member of a set 30 of contacts 119. When the brake pipe 16a is charged with fluid under pressure above a value which is below that to which brake pipe pressure is reduced when effecting a service application of the brakes, the diaphragm 115 is positioned as 35 shown, whereupon contacts 119 are maintained open. When brake pipe pressure is reduced to effect an emergency application of the brakes, the diaphragm 115 moves downwardly, thereby closing contacts 119. 40

The operation of this modification of the afore-described embodiment is as follows:

Operation of the modification shown in Fig. 2

In this modification applications of the brakes 45 are effected in the same manner as described for the embodiment of Fig. 1. It is, therefore, unnecessary to describe in detail again the manner in which both service and emergency applications are effected.

Regardless of what type of application is effected, whenever fluid under pressure is supplied to control pipe 51a, flow is through pipe 73a to chamber 89 in the service sanding switch device 85. Fluid at a low pressure in this chamber will 55 actuate the diaphragm 88 to the right to effect closing of contacts 93. This will supply current from battery 80a to sanding train conductor 82a, to effect the operation of the sanding magnet valve devices 28a on the trailer cars. Sanding 60 will thus result concurrently with the brake application.

If, however, the operator does not desire the automatic sanding, he may depress the button 58a of the suppression valve device 30a and there- 65 by supply fluid under pressure from pipe 59a to pipe 60a, and from thence past the check valve 65a to volume reservoir 33a and chamber 96 of the suppression switch device 86. The dia- 70 phragm 95 in this device will be then shifted upwardly to move the arm 102 to its uppermost position and at the same time open contacts 101. Now if the operation of the suppression valve device 30a takes place before the application is initiated, the upward movement of the arm 102 75

prevents subsequent movement of the stem 91 sufficiently to close contacts 93. Assuming that the operator removes his hand from the button 58a before initiating the brake application, it follows that the arm 102 will remain in its uppermost position, due to fluid pressure in chamber 96, for a predetermined interval of time. If during this interval of time the brake application is effected, the stem 91 of switch device 85 will move to the right and under the latch 105, thus holding the arm 102 in its uppermost position, and thereby maintaining contacts 101 open. The suppression of the automatic sanding will, therefore, be effective throughout the entire brake application and not merely for the time interval during which pressure exists in chamber 96.

If, however, the brake application is not initiated within the said predetermined interval of time, it follows that the suppression will not be effective during the brake application.

If now the suppression is initiated after the brake application is made, it will be apparent that the arm 102 will also be held in its upper position by the stem 91 of the switch device 85, and the suppression will be effective throughout the remainder of the brake application. It will be observed that the diaphragm 95 in the device 86 is considerably larger than the diaphragm 88 in the device 85, so that although the stem 91 has been previously actuated to the right, the force exerted by the diaphragm 95 in moving upwardly is great enough to cause the end 112 of the arm 102 to retract the stem 91 sufficiently to the left to permit movement of the end 112 upwardly until the latch 105 passes above the end of the stem.

From what has been said, therefore, it will be evident that if the suppression of sanding is initiated at any time during a service brake application it will be effective for the remainder of the application.

When an emergency application of the brakes is effected, by reducing the pressure in brake pipe 16a, the diaphragm 115 in the switch device 87 moves downwardly, thereby closing contacts 119. This establishes a circuit from the battery 80a to the sanding train conductor 82a, to the right of contacts 101, by way of conductors 81a, 121, contacts 119, and conductor 122. Thus the entire suppression mechanism is by-passed and automatic sanding will result on the trailer cars.

It is to be noted, however, that since during an emergency application fluid under pressure is supplied to the control pipe 51a automatic sanding would result through operation of the switch device 85, but the effect of operation of the switch device 87 is to prevent any possible suppression of sanding.

Embodiment of Fig. 3

This embodiment comprises the same brake system as shown in the embodiment of Fig. 1, with the addition that on each trailer car an emergency valve device 124 is added and has connected thereto a quick action chamber or reservoir 125. Further, the sanding equipment on each trailer car now includes a sanding valve device 126 and a sanding magnet valve device 127 in the place of the sanding magnet valve device 28 of Fig. 1. The sanding device 26b and the sanding reservoir 27b are the same as the sander 26 and reservoir 27 of Fig. 1.

On the head end car the sanding apparatus now includes the sanding switch device 32b, suppression switch device 128, volume reservoir 129, magnet valve device 130, switch device 131, relay 132, and suppression valve device 133. All parts

of this equipment which are duplicates of the corresponding parts in Fig. 1 are indicated by like numerals with the subscript "b" added.

Considering now the new parts in detail, the emergency valve device 124 is embodied in a casing having slidably disposed therein a piston 135, which is subject on its left hand side to pressure of fluid in chamber 136 and on its right hand side to pressure of fluid in chamber 137 and that in quick action chamber or reservoir 125. The chamber 136 is connected to the brake pipe 16b by branch pipe 138.

Attached to the piston 135 is a stem 139 which is recessed to receive and move coextensive with movement of the piston 135, a graduating slide valve 140, which is disposed on top of a main slide valve 141. The main slide valve 141 is also movable by the stem 139 after a lost motion movement, as is apparent from the drawings.

For holding the main slide valve 141 upon its seat, a seating mechanism comprising a stem 142 is provided. This stem is attached to a diaphragm 143 which is subject on its uppermost side to the combined pressure of a spring 145 and that of fluid pressure in chamber 144. Chamber 144 is in constant open communication by way of passage 146 with a pipe 147 leading to the local supply reservoir 15b.

Disposed in the lower part of the emergency valve device casing is a vent valve 148 which is urged toward a seated position by spring 149, but is adapted to be actuated to an unseated position by a piston 150 upon the supply of fluid under pressure at a predetermined rate to chamber 151. When the vent valve 148 is unseated the brake pipe is vented to the atmosphere at a rapid rate by way of branch pipes 138 and 152, past the unseated vent valve 148 and through exhaust port 153. Fluid pressure in chamber 151 will in time leak away through choke port 155 in piston 150.

When the brake pipe 16b is charged with fluid under pressure to its normal value, the parts of the emergency valve device will be positioned as shown, the position of piston 135 being such that a feed groove 154 provides communication between chambers 136 and 137 so that quick action chamber or reservoir 125 will be charged to brake pipe pressure.

Upon a reduction of brake pipe pressure at a service rate, the preponderant pressure in chamber 137 shifts the piston 135 to the left. As the piston thus moves the graduating valve 140 moves with it until a port 156 therein comes in registration with a port 157 in the main slide valve 141, which at this time is in communication with an exhaust port 158. This causes the pressure of fluid in chamber 137, and in quick action chamber 125, to be reduced at a rate equal to or slightly greater than the service rate of reduction in brake pipe pressure. As a consequence, the motion of the piston 135 to the left is arrested and as brake pipe ceases reducing the further fall of pressure in chamber 137 causes the piston 135 to be moved back to its release position as illustrated.

Upon an emergency reduction of pressure in the brake pipe, the preponderant pressure in chamber 137 causes the piston 135 to move further and more promptly to the left and uncover a port 160 in the main slide valve, which at this time is in communication with the vent valve piston chamber 151. Fluid under pressure is thus supplied from chamber 137 to the piston chamber 151 at a rate sufficient to actuate the vent valve 75

piston 150 downwardly and thus unseat the brake pipe vent valve 148. The unseating of the vent valve 148 causes a sharp drop of pressure in the chamber 136, and as a consequence the piston 135 will then promptly move the main slide valve 141 to its left hand position, where cavity 161 therein connects the supply reservoir pipe 147 to a pipe 162 leading to the sanding magnet valve device 127 on the same car. The local sharp reduction in brake pipe pressure also acts to propagate brake pipe reduction throughout the train at a more rapid rate, as is well understood.

Considering now the magnet valve device 127, this valve device is embodied in a casing having two valves 164 and 165 provided with fluted stems arranged in abutting relationship. A spring 166 acts to urge the valve 165 toward seated position and the valve 164 toward unseated position. An electromagnet 167 in the upper part of the casing operates when energized to shift the valve 164 to seated position and the valve 165 to unseated position.

When the two valves 164 and 165 are positioned as shown communication is established between the aforementioned pipe 162 and a pipe 168 leading to the sanding valve device 126. When the two valves 164 and 165 are urged to seated and unseated positions, respectively, communication between pipes 162 and 168 is closed, and communication is established between pipe 168 and another pipe 169 leading to sanding reservoir 27b.

Considering now the sanding valve device 126, this device is embodied in a casing having a piston 170 which is slidably disposed therein and subject on its uppermost side to pressure of fluid in chamber 171 and on its lowermost side to pressure of fluid in chamber 172, which is open by way of pipe and passage 173 to the sanding device 26b. The piston 170 is adapted to actuate double beat valve 174. The double beat valve is urged to an upper seated position by a spring 175, but when fluid under pressure is supplied to the chamber 171 the piston 170 is actuated downwardly, and a spring pressed plunger 176 engages the fluted stem of the double beat valve 174 to actuate it to a lower seated position. In its lower position the piston 170 engages a gasket 189 thus exposing less than its full area to fluid pressure therebelow.

When the double beat valve 174 is in its upper seated position, as illustrated, communication is established between the local supply reservoir 155 and the sanding reservoir 27b, by way of pipe and passage 163, past the open lower seat of the double beat valve 174, and pipe 169. When the double beat valve 174 is actuated to lower seated position, this communication is closed and the sanding reservoir 27b is connected to the sander 26b, to cause the sander to deposit sand on the track rails.

The switch device 32b is essentially a duplicate of the switch device 32 of Fig. 1, and the parts are similarly numeralized with the subscript "b."

The switch device 128 is embodied in a casing having disposed therein a piston 178 subject on its lowermost side to pressure of fluid in chamber 179 and on its uppermost side to pressure of spring 180. Attached to and insulated from the piston 178 is a movable contact 183, which in the lower position of the piston engages two stationary contacts 181, and in the upper position of the piston engages two stationary contacts 182.

The magnet valve device 130 is embodied in

a casing comprising a valve 184 which is urged toward a seated position by a spring 185, and toward unseated position by an electromagnet 186 when energized. When the valve 184 is in seated position communication is closed between a pipe 187 leading to the brake cylinder 10b on the head end car, and a pipe 188 leading to the switch device 131. When the valve 184 is unseated this communication is open.

The switch device 131 is embodied in a casing containing a piston 190 therein urged downwardly by a spring 191. The piston contains on the face thereof a gasket 192 which is adapted in the lowermost position of the piston to seat upon an annular seat rib 193. The chamber space within this seat rib is open to the aforementioned pipe 187, while the chamber space outside this rib is open to the aforementioned pipe 188.

Carried by and insulated from the piston 190 is a movable member of a set of contacts 195. These contacts are closed when the piston 190 is in its lowermost position, and are opened when the piston is actuated upwardly.

The electrical relay 132 contains two sets of contacts 196 and 197, both of which are adapted to be opened when the relay is deenergized and closed when the relay is energized.

The suppression valve device 133 is embodied in a casing comprising a release valve 198 and supply valve 199 having fluted stems arranged in abutting relationship. The two valves are urged to unseated and seated position, respectively, by a spring 200, and are adapted to be actuated to seated and unseated position, respectively, by pressure manually applied to a knob or button 201.

When the release valve is in unseated position and the supply valve is in seated position, as illustrated, a pipe 202 leading to the switch device 128 is in communication with the atmosphere by way of a restricted port 203. When the valve 198 is actuated to seated position and the valve 199 to unseated position, this communication to the atmosphere is closed and pipe 202 is connected to the feed valve branch pipe 59b.

Operation of the embodiment of Fig. 3

In this embodiment service and emergency application of the brakes are effected and the like parts of the equipment operate in the same manner as described for the embodiment of Fig. 1. Insofar as initiating brake applications are concerned, when an emergency application is initiated the emergency valve device 124 on the cars operates to accelerate the brake pipe reduction throughout the train, and to control sanding operations as will be described presently.

Regardless of the type of applications effected, whenever fluid under pressure is supplied to the control pipe 51b and branch pipe 73b the pressure of this fluid acting in the switch device 32b will cause current to be supplied from the battery 80b to the sanding train conductor 82b to energize the sanding magnet valve device 127 on each car of the train. The valves 164 and 165 of this device will be then shifted to seated and unseated position respectively, so that fluid under pressure will be supplied from the sanding reservoir 27b to the chamber 171 in the sanding valve device 126. The piston 170 will then move downwardly to shift the double beat valve 174 to a lower seated position. As before described, this will connect the sanding reservoir

75

27b to the sanding device 26b, to cause sand to be applied to the rails. This automatic sanding under each of the trailer cars will take place in both service and emergency applications, unless the button 201 of the suppression valve device 133 is depressed, in which case automatic sanding will not be effective in service applications of the brakes.

When the knob 201 of valve device 133 is depressed the valve 198 therein is seated and the valve 199 unseated, so that fluid under pressure is supplied from the feed valve branch pipe 59b through pipe 202 to the volume reservoir 129 and switch device 128. The switch device 128 then opens its contacts 181 and closes its contacts 182. Opening of the contacts 181 de-energizes the sanding train wire 82b to thereby cause the sanding magnet valve devices 127 throughout the train to terminate or prevent sanding under the trailer cars.

Closing of contacts 182 effects the energization of the magnet valve device 130 so as to connect the brake cylinder 10b on the head end car to the chamber space outside of the annular seat rib 193 in the switch device 131. As will be observed, the brake cylinder 10b is at all times connected to the chamber space within the seat rib 193, but the maximum brake cylinder pressure which can be developed during an application will be insufficient to cause upward movement of the piston 190. However, when a nominal brake cylinder pressure is supplied to the much greater chamber area outside the seat rib 193, the piston 190 moves away from the annular seat rib 193, thus exposing the entire lower surface of the piston to brake cylinder pressure. The piston then promptly moves upwardly to open contacts 195. These contacts will, of course, remain open so long as brake cylinder pressure above a predetermined low value exists, which means that the sanding operation will be suppressed substantially throughout the entire brake application.

Now if the operator depresses the button 201 and then releases it after fluid under pressure has been supplied to the volume reservoir 129 and switch device 128, fluid under pressure will be released from these two devices by way of the restricted port 203. This will require a definite interval of time. If the button 201 is depressed before the brake application is initiated and the brake application is initiated within this definite period of time, then the sanding operation will be suppressed throughout the duration of the brake application. If, however, the brake application is effected after the elapse of the said interval of time, contacts 182 will be opened and contacts 181 closed, so that when the brake application is effected automatic sanding under the trailer cars will result.

If the button 201 is depressed after the brake application is effected, it will be apparent that the sanding initiated by the brake application will be terminated and will be suppressed throughout the remainder of the brake application.

Assuming now that the sanding operation has been suppressed with the brakes applied, and that the operator now desires to sand the rails, he may do so by depressing push button 210 and thus closing contacts 211. Remembering that the contacts 72b are now closed but that the contacts 181 are open, and that the contacts 182 are closed, it will be observed that the electrical relay 132 will be energized from the bat-

tery 80b by way of contacts 72b, and the contacts 211 of the push switch. The relay 132 will then close both sets of contacts 196 and 197.

The closing of contacts 196 will provide a holding circuit for the relay 132 so that pressure on the push switch 210 may be released. Closing of contacts 197 establishes a circuit from the battery 80b to the sanding train conductor 82b, by way of the contacts 72b, and relay contacts 197. The suppression devices are thus bypassed by the relay contacts 197, and as a consequence the sanding magnet valve devices 127 throughout the train will be energized and will effect sanding under each of the trailer cars. This sanding will, of course, continue until the brake application is released and contacts 72b thereby opened. This is based on the assumption that the sanding reservoir 27b is made sufficiently large to produce sanding throughout the entire deceleration period.

Now when a service application of the brakes is effected the emergency valve device 124 will function as before described and as a result the main slide valve 141 will not be moved to application position. When, however, an emergency application is effected, the main slide valve 141 will be shifted to application position, connecting pipes 147 and 162 and thus supplying fluid under pressure from the supply reservoir 15b to chamber 171 of the sanding valve device 126. This valve device will then operate to supply fluid under pressure from the sanding reservoir 27b to the sender 26b, to thus cause sanding of the rails.

It will be observed that this sanding operation cannot be suppressed by depressing the knob 201 of the suppression valve device 133. It will be also observed that in the event that no suppression is attempted, the closing of the contacts 72b of the switch device 32b, as a result of the supply of fluid under pressure to the control pipe 51b, will energize the sanding magnet valves 127 throughout the train to accomplish the same result as accomplished by emergency valve device 124. Thus sanding is in any event assured during an emergency application of the brakes, and cannot be intentionally suppressed.

When the brakes are released following an emergency application the contacts 72b of the switch device 32b will be opened, and, also, the parts of the emergency valve device 124 will move to release position to terminate further supply from the local supply reservoir 15b to the pipe 162.

Modification shown in Fig. 4

The modification in this figure deals only with the apparatus on the head end or control car. The parts which are duplicates of those shown in Fig. 1 are indicated by like numerals with the subscript "c" added. The new parts, relating to the sanding apparatus, include a sanding switch device 215, a suppression switch device 216, and an electric relay 217.

Considering the new parts in detail, the switch device 215 contains a piston 218 therein subject on its lowermost side to pressure in chamber 219 and on its uppermost side to pressure of spring 220. The chamber 219 is connected to pipe 73c, a branch from control pipe 51c.

When the piston 218 is in its lowermost position, a movable contact 221 is disengaged from stationary contacts 222, while another movable contact 223 engages stationary contacts 224. As

the piston 218 is actuated upwardly, movable contact 221 engages stationary contacts 222, while movable contact 223 disengages from stationary contacts 224 and then engages stationary contacts 225.

5 The suppression switch device 216 comprises essentially a contact handle 227, which is movable to the right to a position indicated as "Before," or to the left to a position indicated as "After." 10 The handle has secured thereto a magnetic element 228 which, when the handle 227 is in its right hand position, is attracted by an electromagnet 229, when energized, with sufficient force to retain the handle in its right hand position.

15 In its right hand position the contact handle connects contact 230 to a supply conductor 231. In its left hand position the handle 227 connects the supply conductor 231 to two contacts 232 and 233. The handle 227 is normally maintained in 20 its neutral or middle position, as illustrated, by two springs 234 and is moved to either its left or right hand position against the opposition of one of these two springs.

25 The electric relay 217 is of the slow release type, that is to say, it has a movable contact member 238 which is actuated promptly upon energization of the relay, but whose movement is delayed for a short interval of time upon deenergization of the relay. When the relay is deenergized, the 30 movable contact member 238 engages stationary contacts 239 and when the relay is energized the movable contact member engages stationary contacts 240.

35 *Operation of the modification shown in Fig. 4*

Service and emergency applications of the brakes are effected with this modification in the same manner as before described for that of Fig. 1. Whenever fluid under pressure is supplied to the control pipe 51c and branch pipe 73c, flow is to chamber 219 in the sanding switch device 215. Contact member 221 will then engage and close stationary contacts 222, and contact member 223 will disengage from stationary contacts 224 and then engage and close stationary contacts 225.

40 The closing of contacts 222 will, with the handle 227 of the suppression switch device in the illustrated position, cause current to be supplied from the battery 80c to the sanding train conductor 82c, to effect sanding of the trailer cars in the manner heretofore described.

45 The opening of contacts 224 and the closing of contacts 225 performs no function at this time.

50 If before the brake application is effected the operator desires to suppress sanding, the handle 227 is moved to the position indicated as "Before." In this position of the handle current is supplied from the battery 80c to the relay 217, 55 by way of contacts 224, conductor 231, contact 230, and rectifier or valvular device 242, and also to the electromagnet 229, thus holding the handle 227 to the right. The relay will then open its contacts 239 and close its contacts 240. Opening of the contacts 239 prevents the supply of current from battery 80c to the sanding train conductor 82c upon the subsequent closing of contacts 222 when the brake application is effected.

60 When the brake application is effected and fluid under pressure is supplied to the switch device 215 the consequent closing of contacts 225 provides by way of relay contacts 240 a holding circuit for the relay. This holding circuit is not effective in energizing the electromagnet 229, due 65 to the presence of the device 242, so that the

opening of contacts 224 deenergizes the electromagnet 229, and the handle 227 may return to its neutral position. Sanding will thus be suppressed, if no other operation takes place, for the duration of the brake application.

5 If a service application of the brakes is first made, with consequent automatic sanding on the cars, and the operator then desires to suppress the sanding, he moves the suppression switch handle 227 to the position indicated as "After." 10 In this position of the handle electric relay 217 is energized from the battery 80c by way of the now closed contacts 225, push switch 237, contacts 232 and 233, and the rectifier or valvular device 242. As the relay closes its contacts 240 15 the holding circuit previously described will be established. The consequent opening of the contacts 239 of the relay will, of course, deenergize the train conductor 82c and terminate the sanding. Suppression of sanding will, therefore, be 20 effective throughout the duration of the brake application.

25 If automatic sanding has been suppressed, either as a result of moving the switch handle 227 to the right before effecting a brake application, or to the left after effecting the application, and it is desired during the application to utilize the automatic sanding feature, the operator may do so by depressing the push switch 237 and thereby opening the contacts of this switch. It 30 will be observed from the previous discussion that the contacts of this push switch are in the holding circuit of the relay 217. Therefore, when these contacts are opened the relay 217 will be deenergized and the closing of its contacts 239 35 will permit automatic sanding to take place so long as the brake application is effective.

30 While the modification shown in Fig. 4 has not included the feature included in the embodiments of Figs. 1 and 3, whereby during emergency applications automatic sanding is effected regardless of operation of the suppression feature, it 40 will be obvious that the brake system may include this feature in addition to the apparatus shown in Fig. 4.

45 It will thus be apparent from the description of several forms of the invention that there has been provided apparatus for automatically effecting sanding under the trailer cars in a train, with the provision of a manipulative control such that a high degree of flexibility is offered in controlling the sanding operation.

50 While the invention has been illustrated by depicting several forms which it may take, it is to be understood that I do not desire or intend to be limited to the precise forms shown, or otherwise than according to the spirit and scope of the appended claims.

55 Having now described my invention, what I claim as new and desire to secure by Letters Patent, is:

60 1. In a train sanding apparatus, in combination, a train conductor, a plurality of electrically operated sanding devices connected to said conductor and operable when said conductor is energized to effect sanding of the track rails, two independently operable switch devices connected in series between said conductor and a source of current supply, one of said switch devices being normally open and the other of said switch devices being normally closed, means for effecting the closing of said normally open switch device when effecting an application of the train brakes, and means operative to effect the opening of said normally closed switch device before or after 65

effecting an application of the brakes and being operable to maintain said normally closed switch device opened for a predetermined interval of time.

5. 2. In a train sanding apparatus, in combination, a conductor adapted to extend throughout the train, a plurality of electrically operated devices operable upon energization of said conductor for effecting sanding of the rails, a source of 10 current supply, a first switch device operated upon a variation of fluid pressure therein for connecting said conductor to said source of current supply, and a second switch device operated upon an independently caused variation of fluid 15 pressure therein for opening said circuit.

3. In a vehicle sanding apparatus, in combination, a circuit to which current is supplied to effect sanding of the track rails, a first switch device operated upon an increase in pressure there- 20 in for connecting said circuit to a source of current supply, an element having a biased position and being shiftable to an operating position to prevent said first switch device connecting said circuit to said source of supply, and a second de- 25 vice operated upon an increase in fluid pressure therein for shifting said element to said operating position.

4. In a train sanding equipment, in combination, a circuit to which current is supplied to 30 effect sanding of the track rails, a first switch device having normally open contacts adapted to be closed when an application of the brakes is effected to connect said circuit to a source of current supply, means operated upon an increase of 35 fluid pressure therein for preventing the closing of said contacts before they have closed, or for opening said circuit if said contacts have in the meanwhile closed, and means manually operable for effecting a supply of fluid under pressure to 40 said last means.

5. In a train brake equipment, in combination, a pipe to which fluid under pressure is supplied to effect an application of the train brakes, a train conductor extending throughout the train, electrically operated sanding devices connected to 45 said conductor and operable when said conductor is energized to deposit sand on the track rails, a first switch device operated in response to pressure in said pipe for connecting said sanding con- 50 ductor to a source of current supply, a second switch device operable subsequent to operation of said first switch device to disconnect said circuit from said source of current supply, means for effecting and maintaining a fluid pressure in 55 said second switch device for a predetermined interval of time, and means for maintaining said conductor disconnected from said source of supply after said predetermined interval of time and so long as the train brakes shall be applied.

6. In a train brake system, in combination, a pipe to which fluid under pressure is supplied to effect an application of the brakes, a conductor extending throughout the train, a plurality of electrically operated devices connected to said 60 conductor and operable upon energization there- 65 of to effect sanding of the track rails, a first switch device responsive to pressure of fluid in said pipe for connecting said conductor to a source of current supply, a second switch device operable upon supply of fluid under pressure thereto to disconnect said conductor from said 70 source of current supply, manually controlled means for effecting supply of fluid under pressure to said second switch device and for maintaining 75 fluid pressure therein for a predetermined inter-

val of time, and means effective when both of said switch devices have been operated for maintaining said conductor disconnected from said source of supply beyond said predetermined interval of time and so long as said brake applica- 5 tion shall be effective.

7. In a train brake system, in combination, a communication through which fluid under pressure is supplied to effect an application of the brakes, a conductor extending throughout the train, a plurality of electrically operated devices operable upon energization of said conductor for effecting sanding of the track rails, a switch device responsive to the pressure of fluid supplied through said communication for connecting said conductor to a source of current supply, fluid pressure operated means operable before a brake application is initiated to prevent connecting of said conductor to a source of current supply, and operable after a brake application has been initiated to disconnect said conductor from said source of current supply, valve means having a manually actuated element and being operable so long as pressure is manually applied to said element to effect a supply of fluid under pressure to 25 operate said fluid pressure means, and being operable upon release of pressure on said element to effect a release of fluid under pressure from said fluid pressure means, and means restricting the rate of release of fluid pressure from said fluid pressure means whereby to delay the operation thereof due to said release of fluid pressure for a predetermined interval of time.

8. In a train brake system, in combination, means for effecting a service application or an 35 emergency application of the brakes, a conductor extending throughout the train, a plurality of electrically operated devices connected to said conductor and operable upon energization there- 40 of to effect sanding of the track rails, means oper- 45 able upon effecting a service application of the brakes for connecting said conductor to a source of current supply, manually operable means operable before or after effecting a service application of the brakes to suppress the operation of said last means, and means operable when an emer- 50 gency application of the brakes is effected for connecting said conductor to a source of current supply independently of the operation of said suppression means.

9. In a train brake system, in combination, a pipe to which fluid under pressure is supplied to effect a service application of the brakes, a normally charged pipe in which the pressure of fluid is reduced to effect an emergency application of 55 the brakes, a conductor extending throughout the train, a plurality of electrically operated devices connected to said conductor and operable upon energization thereof to effect sanding of the track rails, a first switch device responsive to the pres- 60 sure of fluid in said first mentioned pipe for connecting said conductor to a source of current supply, manually operated means effective before or after operation of said first mentioned switch device for preventing the connecting of said conductor to said source of current supply, and means operated upon a reduction of pressure in said normally charged pipe for connecting said conductor to said source of current supply inde- 65 pendently of operation of said aforementioned means.

10. In a train sanding apparatus, in combination, a train conductor, a plurality of sanding devices operable upon energization of said conductor for effecting sanding of the track rails, two 75

- sets of contacts arranged in series, one of said sets of contacts being normally opened and the other being normally closed, said sets of contacts being operative when closed simultaneously to 5 connect said conductor to a source of current supply, and either of said sets of contacts being operable when open to disconnect said conductor from said source of current supply, means operable to close said normally open set of contacts 10 when effecting a service application of the brakes, manually controlled means operable at any time to effect the opening of said normally closed set of contacts, and means operable when effecting an emergency application of the brakes for establishing a by-pass circuit around said two sets of contacts whereby to connect said conductor to said source of current supply independently of 15 operation of said two sets of contacts.
11. In a train brake system, in combination, a plurality of electrically operated devices for effecting sanding of the track rails each of which is disposed on a separate car in the train, means on one car in the train for effecting the operation of all of said electrically operated devices when 20 effecting an application of the brakes, means operative at the will of an operator before or after effecting an application of the brakes for suppressing the operation of said sanding devices for a predetermined interval of time, and means effective when an application of the brakes is effected within said predetermined interval of time for causing the suppression of said sanding devices to be effective throughout the duration of 25 the brake application.
12. In a train brake system, in combination, a plurality of electrically operated sanding devices each of which is located on one car in the train for effecting sanding of the track rails, means operative upon effecting an application of the 30 train brakes for effecting the operation of said sanding devices, means manually operable at the will of an operator either before or after the brake application is effected for suppressing the operation of said sanding devices, and means also manually operable at the will of an operator and independently of the last mentioned means, for effecting a further sanding operation of said sanding devices following suppression thereof by 35 said last mentioned means.
13. In a train brake system, in combination, braking apparatus for the train including a plurality of brake cylinders, a conductor extending throughout the train to which current is supplied to effect sanding of the track rails by devices on 40 one or more of the cars in the train, a source of current supply, a first switch device operated when a brake application is initiated for connecting said train conductor to said source of current supply, manually controlled means including a second switch device operable at the will of an operator for disconnecting said conductor from said source of current supply for a definite interval of time, and means including a third switch device controlled by said second switch device for 45 controlling the disconnection of said conductor from said source of current supply for an indefinite interval of time.
14. In a train brake system, in combination, braking apparatus for the train including a plurality of brake cylinders, a conductor extending throughout the train and to which current is supplied to effect sanding of the track rails by devices on one or more of the cars in the train, a source of current supply, a first switch device operated when a brake application is initiated for 50
- connecting said train conductor to said source of current supply, manually controlled means including a second switch device operable at the will of an operator for disconnecting said conductor from said source of current supply for a predetermined interval of time, and means including a third switch device controlled by said second switch device for controlling the disconnection of said conductor from said source of current supply for an indefinite period of time, said third switch device being subject to fluid at brake cylinder pressure.
15. In a vehicle brake control system, in combination, a conductor, at least one electrically operated device connected to said conductor and operable upon supply of current thereto for effecting sanding of the track rails, three switch devices arranged in series and being operable when all of said switch devices are closed simultaneously to connect said conductor to a source of current supply, means controlled by the brake control apparatus for controlling the operation of one of said switches, suppression means manually controlled at the will of an operator for controlling the operation of a second of said switches, and means controlled in part by brake cylinder pressure for controlling the third of said switches.
16. In a vehicle brake control system, in combination, a conductor, at least one electrically operated device connected to said conductor and operable upon supply of current thereto for effecting sanding of the track rails, three switch devices arranged in series and being operable when all of said switch devices are closed simultaneously to connect said conductor to a source of current supply, means controlled by the brake control apparatus for controlling the operation of one of said switch devices, suppression means manually controlled at will by an operator for controlling the operation of a second of said switch devices, means controlled in part by brake cylinder pressure for controlling the third of said switch devices, and means also manually controlled at the will of the operator for establishing a by-pass circuit around said second and third switch devices.
17. In a train brake system, in combination, a plurality of braking units each of which is located on one of the cars in the train, means for effecting service application of the brakes including a pipe to which fluid under pressure is supplied to initiate the application, means for effecting emergency application of the brakes including a normally charged pipe in which the pressure of fluid is reduced to initiate the application, a plurality of sanding devices each of which is located on one of the cars in the train, means controlled by the pressure of fluid in said first mentioned pipe for controlling the operation of said sanding device throughout the train, means operable at the will of an operator for suppressing the effective operation of said last mentioned means, and means controlled by the pressure of fluid in said normally charged pipe for controlling the operation of said sanding devices independently of operation of said first mentioned control means.
18. In a vehicle brake system, in combination, means automatically operative when initiating an application of the brakes for sanding the track rails, means operative at the will of an operator before or after initiating the brake application for suppressing the operation of said sanding means, and means also operative at the will of an operator subsequent to suppression

- of the sanding means for effecting the operation of said sanding means independently and regardless of previous operation of the suppression means.
- 5 19. In a vehicle brake and sanding system, in combination, a train conductor, a plurality of electrically operated sanding devices connected to said conductor and operable when said conductor is energized to effect sanding of the track rails, two independently operable switch devices connected in series between said conductor and a source of current supply, one of said switch devices being normally opened and the other being normally closed, means for effecting the 10 closing of said normally open switch device whenever an application of the train brakes is effected, and means operable independently of the train brake application for effecting quickly the opening of said normally closed switch device either 15 before or after effecting an application of the train brakes and for thereafter effecting closing of the same switch device with a delayed operation.
20. In a train brake and sanding equipment, 20 in combination, an electrical circuit adapted to extend throughout the train, electrically operated sanding devices actuated upon supply of current to said circuit for effecting sanding of the track rails, a source of current supply, a switch device connected in series between said conductor and a source of current supply, one of said switch devices being normally opened and the other being normally closed, means for effecting the closing of said normally open switch device whenever an application of the train brakes is effected, and means operable independently of the train 25 brake application for effecting quickly the opening of said normally closed switch device either before or after effecting an application of the train brakes and for thereafter effecting closing of the same switch device with a delayed operation.
21. In a vehicle brake and sanding system, in combination, means for effecting an application of the vehicle brakes, means operative whenever an application of the vehicle brakes is initiated for automatically causing sanding of the track rails, a handle having a biased position and movable in one direction to a first operative position and also in an opposite direction to a second operative position, means responsive to movement of said handle to said first operative position prior to initiating the brake application or movement of said handle to said second operative position subsequent to initiating the brake application for suppressing the operation of said sanding means, and a device operatively responsive to mere touch by an operator for nullifying the effect of said last mentioned means.

CLYDE C. FARMER.

the track rails, a source of current supply, means operable whenever an application of the train brakes is effected for connecting said circuit to said source of current supply to effect sanding of the track rails, and means independent of the train brake application and selectively operable before or after the operation of said last mentioned means for quickly disconnecting said source of current supply and for then at will reconnecting said source with a delayed action.

21. In a vehicle brake and sanding system, in combination, means for effecting an application of the vehicle brakes, means operative whenever an application of the vehicle brakes is initiated for automatically causing sanding of the track rails, a handle having a biased position and movable in one direction to a first operative position and also in an opposite direction to a second operative position, means responsive to movement of said handle to said first operative position prior to initiating the brake application or movement of said handle to said second operative position subsequent to initiating the brake application for suppressing the operation of said sanding means, and a device operatively responsive to mere touch by an operator for nullifying the effect of said last mentioned means.
